UNITED STATES PATENT OFFICE.

LUTHER R. FAUGHT, OF PHILADELPHIA, PENNSYLVANIA.

CHILL FOR CAR-WHEELS.

SPECIFICATION forming part of Letters Patent No. 402,664, dated May 7, 1889.

Application filed April 7, 1887. Serial No. 234,065. (No model.)

To all whom it may concern:

Be it known that I, LUTHER R. FAUGHT, of the city and county of Philadelphia, in the State of Pennsylvania, have invented a certain new and useful Improvement in Chills for Car-Wheels, of which improvement the following is a specification.

In the manufacture of cast-iron chilled wheels and tires two classes of chills, possessing, respectively, distinctively different features, have heretofore been and are at present employed. That which was first introduced and is most generally in use is a metallic mold formed of a solid or undivided ring of iron corresponding in internal form and dimensions with the tread of the wheel desired and the inner face of its flange, when, as is generally the case, it is to be provided with a flange. Chills of such character, when heated by the molten metal poured thereinto, are immediately expanded outwardly by the sudden and material increase of temperature thereby imparted to them. The class of chills more recently devised, and introduced to a considerable extent in practice, comprehends those formed of a solid or undivided outer section and an inner section which is partially or fully divided throughout into a circular series of segmental blocks, united by bars or arms to the outer section and forming the inner face of the chill. These chills expand inwardly upon receiving and being heated by the molten metal, thereby contracting their inner faces, and are therefore known generically as "contracting" chills.

My invention relates to chills of the class last specified, and its object is to promote the contraction of the chill at the pouring of the molten metal, in order that the inner section of the chill may, by abutting closely and uniformly against the outer surface of the cast metal, properly and thoroughly effect the desired chilling of the tread or rim of the wheel.

To this end my invention, generally stated, consists in a contracting chill having its inner and outer sections connected by bars so formed as to be subjected as fully as practicable to the action of the heat imparted from the molten metal, and thereby to exert by their expansion a corresponding tendency to

inward movement upon the members of the inner section of the chill.

The improvement claimed is hereinafter fully set forth.

In the accompanying drawings, Figure 1 is 55 a plan or top view of a portion of a chill embodying my invention, showing also a plan of portion of the cope; and Fig. 2 a vertical section through the cope, chill, and drag at the line $\alpha\alpha$ of Fig. 1. 60

In the practice of my invention I construct a chill which, as in prior instances of the class of contracting chills, is composed of a solid or continuous outer section or rim, 1, and an inner section formed of a circular series 65 of chilling blocks or segments, 2, arranged closely adjacent one to the other, the inner surface of the ring or section formed by the series of blocks corresponding substantially with the treads of the wheels to be cast 70 and being exposed to direct contact with the molten metal. The inner and outer sections are connected by a series of arms or expansion-bars, 3, each extending from one of the blocks of the inner section to the outer section. 75 The blocks or segments 2 and expansion-bars 3 are herein shown, and are preferably, cast integral with the outer section, 1, the blocks 2 being separated one from the other by narrow radial splits or divisions 4, 80 which may be formed either by the insertion of suitable dividing-pieces in the mold in casting the chill or by sawing out subsequently thereto. The chill rests upon a drag, 7, having a bottom plate, 8, and a cope, 9, is 85 placed upon its top, these members providing proper facilities for molding the wheel in the usual manner.

The governing principle of the class of contracting chills to which my invention relates, 90 and which is exemplified in the chill herein shown and described, is the contraction of the chill toward and upon the tread of the wheel by the inward expansion of its inner section and the connecting-bars when heated 95 by the contact of the molten metal poured into the mold with the inner section of the chill. The capacity of contraction of the solid metal of the chill being obviously unequal to the shrinkage which occurs in the solidifica- 100

tion of the molten metal which forms the wheel, the chill cannot move inwardly toward the face or tread of the wheel with the same rapidity that the metal of the wheel shrinks or contracts in the same direction. The wheel being primarily hot molten metal and the chill cold solid metal, and the latter abstracting heat from the former, it is impossible for it to acquire a degree of temperature equal to that of the source from which its heat is derived, and consequently the greater rapidity of contraction will necessarily be induced in the wheel. The wheel therefore tends to recede from the inner surface of the chill, and the result of such tendency is adverse to the proper and thorough chilling of the tread, which is desired to be effected. It will hence be seen that the contractile force should be stimulated in the chill and rendered as fully as possible available in the wheel, to which object my invention is particularly directed.

As heretofore constructed, so far as my knowledge and information extends, the expansion or connecting bars of contracting chills have been formed without regard to the furtherance of coincident contraction of the wheel and chill, they having been extended to the parting-lines at which the cope and drag, together with the sand, are in contact with the chill, thereby exposing the upper and lower faces of the bars to portions of the mold which remain comparatively cool throughout the process of casting, and which would therefore tend to maintain the temperature of the upper and lower faces of the bars at a degree below that which would be imparted to their central portions, and which is necessarily the maximum. Under my invention I relieve, as far as practicable, the expansion-bars 3 from the cooling action above indicated and enable their capacity of expansion to be exerted to a higher degree than heretofore by forming said bars of less depth than the inner section of the chill, with their upper and lower sides out of line with or clear of the upper and lower faces of the inner section of the chill, thus removing the bars from contact with those portions thereof—to wit, the flange and sand edge portions—which adjoin the cope and drag. By such construction the retardation of the expansion of the bars 3 by the abstraction of heat therefrom by comparatively cool portions of the mold is prevented and a higher average temperature is imparted to the bars by the molten metal, with the result of increased expansion of the bars and consequent contraction or inward movement of the inner chill-section, the advantage of which in the production of a uniformly and thoroughly chilled wheel has been hereinbefore indicated.

Fig. 2 illustrates an expansion-bar embodying the principle of my invention, the reduction in depth of which bar and difference of location of its top and bottom surfaces rela-

tively to the ordinary construction is carried out by forming its lower side substantially in line with the rail-line of the wheel or line of contact of the rail and flange when in service, and in correspondingly depressing its upper side 70 below the top of the chill, so as to be slightly below the "sand-edge" portion of the wheel. A bar reduced in depth and located as to the parting-lines of the chill in the proportion as above will be found to carry out my 75 improvement in practice in a desirable manner; but it will be obvious that such proportion of reduction of depth and relative level of the bar may be varied within reasonable limits in the discretion of the constructor without departing from the spirit of my invention. In the instance shown the bars are formed of uniform width throughout their length; but they may, if preferred, be slightly tapered outwardly, so as to be of greater width at their 80 junction with the outer section of the chill than at their inner ends.

In the operation of contracting chills of the general type known prior to my present invention, as exemplified in Letters Patent of 90 the United States No. 341,326, granted and issued to me under date of May 4, 1886, the action of the molten metal when brought in contact with the inner sections of the chill is to induce a stronger and more rapid inward 95 expansion of the portions of said sections at and adjacent to a horizontal plane passing intermediate between their upper and lower faces than at the portions adjacent to said faces, thereby tending to change the vertical 100 planes of their inner walls from substantially straight to slightly-curved lines, and thus to induce a less depth of chill toward their tops and bottoms than at their intermediate portions. This unequal expansion is due to 105 the cooling and retarding action of the colder portions of the mold upon the closely-adjoining portions of the expansion-bars connecting the inner and outer sections of the chill. By forming said bars of reduced depth and connecting them to the inner sections within and entirely clear of the parting-lines between the chill and the cope and drag I not only promote the inward expansion of the inner sections, but obviate the tendency to distortion 110 and unequal chilling above mentioned, a result which is of material importance and practical value in enhancing the soundness and durability of the wheel and facilitating compliance with the comparatively rigid requirements provided by railroad companies in their regulations as to the inspection and test of chilled wheels purchased from manufacturers.

I claim as my invention and desire to secure 125 by Letters Patent—

1. In a contracting chill, an expansion or connecting bar of reduced depth relatively to the inner section of the chill and having at its junction therewith its top face depressed 130

below the top of said inner section and its bottom face elevated above the bottom thereof, substantially as set forth.

2. The combination, in a chill, of a continuous rim or outer section, an inner section composed of a divided circular series of chilling blocks or segments, and a series of expansion-bars connecting the outer to the

inner section and united to the latter wholly within and clear of its parting-faces, substantially as set forth.

LUTHER R. FAUGHT.
